LIQUID DETERGENT COMPOSITION

Norman R. Smith, Cincinnati, Ohio, assignor to The Procter & Gamble Company, Cincinnati, Ohio, a corporation of Ohio

No Drawing. Filed Nov. 14, 1960, Ser. No. 68,652

5 Claims. (Cl. 252—137)

This invention relates to opaque built liquid detergents of the medium-duty and heavy-duty type. More particularly, it relates to such liquid detergents which contain a unique opacifying agent and have improved sudsing and detergent characteristics.

A built detergent is one which contains, in addition to at least one organic surface active agent, a soluble salt capable of sequestering calcium and magnesium ions of hard water and also capable of increasing the level of detergent effectiveness of the surface active agent. In recent years, built liquid detergents have, to some extent, replaced built granular detergents for various reasons. These reasons include: complete freedom from dustiness, compact package and convenience in pouring and measuring. In addition, from the manufacturers standpoint, liquid detergents offer relative simplicity in manufacturing techniques.

The primary problem which has to be overcome in formulating built liquid detergents which are "homogeneous" in nature is that of incorporating sufficient surface active agent and builder into the same solution. (By "homogeneous" as used herein is meant free from a precipitate of detergent actives.) In current practice anionic sulfated or sulfonated compounds are ordinarily used as surface active agents, and potassium pyrophosphate is used as the builder. Various surface active agents, hydrotropes and solvents are employed to increase their compatibility. The fact that the builder may corrode non-ferrous metals such as aluminum, may, depending on the use for which the product is intended, lead the manufacturer to include sodium silicate in the formulation as a corrosion inhibitor. However, with the addition of sodium silicate, special measures have to be taken to prevent the loss of homogeneity of the liquid formulation. For example, limitations on the pH of the formulation or the addition of agents designed to achieve compatibility among its constituents is usually required.

Compositions thus formulated are generally clear liquids of relatively low viscosity. As a manifestation of the compatibility of the ingredients, such physical characteristics are desirable; however, it has been found that these characteristics tend to create the impression that the product is dilute and therefore incapable of accomplishing its purpose unless large quantities are used. As a result, there is a tendency on the part of the consumer to exceed recommended product usage levels, a practice which gives rise to uneconomical usage and decreased detergent effectiveness due to excessive sudsing.

In order to dispel this impression and alleviate this problem, various measures have been taken to modify such liquid detergent formulations. Such measures include rendering the solution opaque through the addition of various opacifying agents and/or increasing the viscosity of the solution by selection of detergent actives or through the addition of various thickening agents. The materials which may be used for this purpose in the

2

case of built liquid detergents are very limited. Generally, inert plastic materials are employed which effectively opacify the liquid, but serve no other useful purpose.

It is an object of this invention to provide a stable opaque built liquid detergent having improved sudsing and detergent characteristics.

A further object of this invention is to provide a stable, opaque built liquid detergent of increased viscosity.

These and other objects are accomplished by employing in the detergent formulations herein defined a borate salt as an opacifier and viscosity modifying agent.

In the following disclosure of the invention, percentages refer to weight percent of the total formula unless otherwise indicated. It will be appreciated that the alkali metal salts may be used interchangeably, since in an aqueous system it is for the most part immaterial how a particular ion is introduced, there being a substantially complete and continuous exchange of ions among the components of the system.

In general, formulations such as the following comprise the invention: (1) from about 2% to about 15% of an alkali metal salt of a borate anion, the said salt having a solubility in water of not more than 5% at 25° C. and being sufficient to yield an opaque solution having a viscosity of at least about 350 centipoises at 75° F.; (2) from about 3% to about 10% of an aliphatic tertiary amine oxide; (3) from about 3% to about 15% of a non-soap synthetic detergent of the sulfated or sulfonated type; (4) from about 3% to about 10% of a soluble hydrotrope; and (5) from about 10% to about 30% of a soluble pyrophosphate salt. The organic detergent actives, hydrotrope and phosphate are dissolved in an aqueous vehicle and the borate salts are added to the solution. When the use of the formulation makes a corrosion inhibitor desirable, from about 3.5% to about 6% of alkali metal silicate solids are dissolved in the same solution.

The alkali metal borates which find utility in this invention have a solubility of 5% or less in water at 25° C. Borates of greater solubility do not yield compositions having the opaque, viscous character desired in the practice of this invention. Of the alkali metal borates which fall within the limitation defined above, sodium tetraborate decahydrate (borax, sodium borate, U.S.P. XIII), $Na_2B_4O_7 \cdot 10H_2O$ or $Na_2O \cdot 2B_2O_3 \cdot 10H_2O$ and potassium pentaborate, $KB_5O_8 \cdot 4H_2O$ or $K_2O \cdot 5B_2O_3 \cdot 8H_2O$ are especially efficacious.

The borate salt must comprise from about 2% to about 15% by weight of the total composition. Less than 2% of this component will not yield the preferred degree of opacity and viscosity, i.e., the solution will be clear or translucent rather than opaque and will have a viscosity of less than 350 centipoises at 75° F. Amounts greater than 15% will adversely affect the stability and homogeneity of the solution. Preferably, this component should comprise from about 4% to about 10% by weight of the total composition.

Amine oxides, which are essential components of the detergent compositions of this invention, are compounds of the general formula $R_1R_2R_3N \rightarrow O$. The arrow is a conventional representation of a semipolar bond. They are generally prepared by the direct oxidation of the appropriate tertiary amine. When R_1 is a much longer chain than R_2 and R_3 , amine oxides have surface activity.

For the purpose of this invention R_1 is an alkyl radical of from about 10 to about 16 carbon atoms. Desirable surface active properties are lost if R_1 is substantially less than 10 carbon atoms, and solubility in the formulation of this invention is too low if R_1 is greater than 16 carbon atoms. Preferably, R_1 is a dodecyl radical or a mixture of dodecyl with decyl, tetradecyl and hexadecyl radicals, such that at least 50% of the radicals are dodecyl radicals. A convenient source of the preferred mixture of alkyl radicals designated R_1 is the middle cut of coconut fatty alcohol which has the approximate chain length composition: 2%— C_{10} , 66%— C_{12} , 23%— C_{14} , and 9%— C_{16} .

R_2 and R_3 are each selected from the group consisting of methyl and ethyl radicals. Preferably, R_2 and R_3 are methyl radicals.

The amine oxide is used at from about 3% to about 10% of the total formula. Less than about 3% amine oxide adversely affects the performance of the formulations and more than about 10% amine oxide interferes with achieving homogeneity between builder and detergent when present in the liquid formulation in sufficient amounts.

Soluble pyrophosphate salts are suitable builders in the liquid detergent compositions of this invention. They complex the calcium and magnesium ions of hard water; and, when the calcium ions of hard water are present in excess, have an additional water softening effect by precipitating calcium pyrophosphate. They also serve to increase the level of detergency obtainable with synthetic non-soap surface active agents. Potassium, sodium, ethanolammonium, diethanolammonium, and triethanolammonium are suitable salts of the pyrophosphate anion in the practice of this invention. Potassium pyrophosphate is especially preferred. The soluble salt of pyrophosphate is employed at a level of from about 10% to about 30%.

The pyrophosphate salts, like various other sequestering agents, are corrosive towards aluminum. If the detergent solution is to contact this metal repeatedly or for prolonged periods of time, especially at elevated temperatures, a corrosion inhibitor should be desirably included. Soluble silicates are highly effective inhibitors and can be added to the formulas of this invention at levels of from about 3.5% to about 6%. Potassium, or preferably sodium silicates having a weight ratio of SiO_2/M_2O of from about 1.0 to about 2.6 and preferably from about 1.6 to about 2.6 can be used. "M" in this ratio refers to sodium or potassium. Less than about 3.5% of silicate solids, although usable in the present compositions, does not provide protection against corrosion in heavy duty use conditions, and more than about 6% of silicate solids has an adverse effect upon the desired homogeneity of the liquid composition.

Suitable hydrotopes to increase the compatibility of the ingredients in the formulations of this invention are the aryl sulfonates. More specifically, they are soluble salts of the hydrotope anions. Preferred salts of hydrotope anions are benzene sulfonate, xylene sulfonate and toluene sulfonate. They are used as the soluble salts such as: ethanolammonium, diethanolammonium, and triethanolammonium and especially as the alkali metal, potassium or sodium, salts. Sodium or potassium toluene sulfonate is especially preferred. The hydrotope salt is added at levels of from about 3% to about 10% and sufficient to achieve homogeneity in the detergent solution. Levels of from about 4% to about 6% are preferred. The upper limit of about 10% is dictated by the dilution effect on the product of an ingredient which is substantially inert so far as sudsing and detergency are concerned. The lower limit is the amount required to achieve a homogeneous solution. It will be appreciated that it is necessary that the formulations of this invention should be liquid at somewhat higher and somewhat lower temperatures than usual room temperature. The amount of hydrotope salt used is preferably the minimum amount

which will prevent precipitation of the detergent actives throughout the temperature ranges to which the product is likely to be subjected.

It has been found that in order to achieve the objects of this invention, a non-soap anionic synthetic detergent must also be present in the detergent compositions contemplated herein. From about 3% to about 15% of anionic detergent is employed. Preferred anionic detergents which have been found beneficial for purposes of this invention are: alkyl benzene sulfonate, alkyl ethylene oxide ether sulfate wherein there are from 1 to 5 ethylene oxide residues per alkyl group, and alkyl sulfate. The anions of these anionic detergents may be represented, respectively, as:

15

$R(OC_2H_4)_xSO_4^-$ — where x is an integer from 1 to 5, and RSO_4^- . In these compounds the alkyl chain (R) will contain from about 9 to about 16 carbon atoms and preferably about 12 carbon atoms. Mixtures of alkyl radicals of different chain lengths are preferably used since they are readily soluble and available from a synthetic source such as a mixture containing tri-, tetra-, and penta-20 polypropylene polymers and averaging about 12 carbon atoms obtained from petroleum hydrocarbons or from natural sources, such as the mixture of fatty alcohols derived from coconut oil. These detergents are, of course, used in the form of their water soluble salts; specifically, 25 they are used as sodium, potassium, ethanolammonium, diethanolammonium, and triethanolammonium salts. The sodium and triethanolammonium salts are preferred.

Although alkyl benzene sulfonate and alkyl sulfate are especially preferred, other non-soap anionic synthetic detergents, containing alkyl radicals as specified above, can be usefully employed in the compositions of this invention if they have the following characteristics: their salts, as specified above, are soluble to the extent of at least 3% in an aqueous solution consisting of a mixture of 3% dimethyldodecylamine oxide, 3% potassium toluene sulfonate, 10% potassium pyrophosphate, and 2% potassium borate; and they are stable against hydrolysis in alkaline solution. An example is the potassium salt of the sulfated condensation product of four moles of ethylene oxide 30 with a mole of nonyl phenol.

Because of the presence of the amine oxide, the compositions of this invention suds so well in the laundry and dishpan that no suds builder is required. Among the anionics, the alkyl sulfate and alkyl benzene sulfonate 35 make a particular contribution to sudsing in the compositions of this invention. Alkyl benzene sulfonate as hereinbefore defined is particularly favored for this purpose because in most circumstances it reduces the cost of the formula.

55 The anionic detergent can tend to improve the mildness of the formulations, alkyl benzene sulfonate being particularly noteworthy in this respect.

Anionic detergents also permit the incorporation of higher levels of active ingredients in a given amount of 60 solvent (water) while still maintaining homogeneity of the liquid composition, i.e., the composition can be made more concentrated.

Preferred compositions of this invention will include 65 two anionic detergents, for example, C_{12} -alkyl benzene sulfonate and coconut alkyl sulfate in approximately equal quantities. If more of one detergent is used, preferably less of another is used. To maintain the homogeneous character of the product, the sum of anionic detergent and amine oxide is preferably kept in the range of from about 70 10% to about 25% by weight of the total composition.

The inorganic builder content is preferably raised as the total synthetic detergent content is lowered; so that the sum of builder and detergent is kept within the range of about 25% to about 40% by weight of the total composition. It has been found that if these limitations are ob-

served, the product will have particularly good performance characteristics and will be homogeneous in nature.

As a rough generalization, when the total amount of synthetic detergent is greater than the amount of builder in the composition, the product is of medium-duty type and can be recommended for hand laundering of fine fabrics and dishwashing. When the detergent level is lower than or equal to the amount of builder, the product is considered to be of the heavy-duty type and is especially adapted for laundry and general purpose use. Because of the generally greater tendency of heavy-duty detergents to damage aluminum as a result of their high phosphate content, it is particularly desirable to include a corrosion inhibitor, e.g. sodium silicate, in such products.

It is to be understood that other materials which are considered normal and desirable additives in detergent compositions can also be added to the compositions of this invention if desired. For example, a tarnish inhibitor such as benzotriazole or ethylene thiourea may be added in amounts up to about 1%. Fluorescers, perfume, color and antiredeposition agents, while not essential in the compositions of the invention, may also be added, usually in amounts less than about 1% of each.

The mole ratio of potassium (plus alkanolammonium ions if present) to sodium should be maintained above about 3:1 to prevent precipitation of the detergent actives.

The term "coconut" as used in the following examples refers to alkyl groups which are derived from middle cut coconut alcohol having the following approximate composition: 2% C₁₀, 66% C₁₂, 23% C₁₄, and 9% C₁₆.

Example I

The following composition was prepared. It was an opaque homogeneous viscous liquid at room temperature.

Dimethyldodecylamine oxide	percent	6.0
Triethanolamine salt of alkyl benzene sulfonate wherein the alkyl group is a mixture of tri-, tetra-, and pentapropylene and has an average carbon atom content of about 12	percent	6.0
Potassium pyrophosphate	do	25.0
Potassium toluene sulfonate	do	8.5
Sodium tetraborate decahydrate	do	5.0
Sodium silicate solids (SiO ₂ :Na ₂ O ratio is 1.6)	do	5.0
Water	Balance	45
K ⁺ triethanolammonium/Na, approx. mole ratio		5.5

The viscosity of this formulation was determined using a Brookfield viscometer and was found to be 540 centipoises at 75° F. Prior to the inclusion of the borate, the formulation had a viscosity of 45 centipoises at 75° F.

The suds obtained from this product were more stable than suds obtained from commercially available built liquid detergents in a comparison test involving the washing of soiled dishes. Also, this product showed good sudsing and cleaning characteristics in washing soiled clothing.

The above formulation was modified by replacing sodium tetraborate decahydrate with potassium pentaborate. This product also had the characteristics noted above.

Example II

The following composition was prepared and examined.

Dimethyldodecyl amine oxide	percent	4.0
Sodium alkyl benzene sulfonate benzene wherein the alkyl group is a mixture of tri-, tetra- and penta- propylene and has an average carbon atom con- tent of about 12	percent	4.0
Sodium coconut sulfate	do	4.0
Potassium toluene sulfonate	do	6.0
Potassium pyrophosphate	do	18.0
Sodium silicate solids (SiO ₂ :Na ₂ O is 2.5-2.6:1)	do	3.8
Perfume, q.s.		75

Water	Balance
K/Na, approx. mole ratio	4.1

The above composition was clear and watery, but on the addition of 5% by weight of the total composition of sodium tetraborate decahydrate changes to an opaque, homogeneous solution having a substantially increased viscosity.

The product proved to be superior to commercially available built liquid detergents in maintaining suds during the washing of soiled dishes when tested under the same conditions.

Example III

The following composition was prepared and found to be a clear, dilute appearing liquid.

Dimethyldodecyl amine oxide	percent	8.0
Sodium coconut sulfate	do	4.0
Potassium toluene sulfonate	do	6.0
Potassium pyrophosphate	do	18.0
Sodium silicate solids (SiO ₂ :Na ₂ O is 2.5- 2.6)	do	3.8
Water	Balance	5.0
K/Na, approx. mole ratio		5.0

The addition of 5.0% by weight of the total composition of sodium tetraborate decahydrate renders the clear solution opaque and substantially increases its viscosity. The product proved superior to commercially available built liquid detergents in suds stability.

The sodium silicate can be omitted from the compositions of the foregoing examples without substantially affecting their appearance or performance. Dodecyl radicals and the mixture of alkyl radicals derived from coconut oil are substantially equivalent, that is, one can be substituted for the other in the ingredients of this example with no substantial change in appearance or performance of the product. Potassium benzene sulfonate or potassium xylene sulfonate can be used to replace potassium toluene sulfonate without losing the opaque homogeneous viscous nature of the product or adversely affecting its performance. Similarly, potassium pentaborate may replace sodium tetraborate decahydrate without loss of these desirable characteristics.

Example IV

The following compositions are opaque homogeneous viscous liquids at room temperature.

	A, percent	B, percent
Dimethyldodecyl amine oxide	5.0	6.0
Sodium coconut ethylene oxide ether sulfate (average of 3 ethylene oxide residues per molecule)	8.5	10.0
Sodium coconut sulfate	2.5	
Sodium alkyl benzene sulfonate wherein the alkyl group is a mixture of tri-, tetra- and pentapropylene and has an average carbon atom content of about 12	4.0	4.0
Potassium pyrophosphate	12.0	12.0
Potassium toluene sulfonate	5.0	5.0
Sodium tetraborate decahydrate	3.0	8.0
Color	0.0013	0.0013
Benzotriazole	0.02	0.02
Water	Balance	Balance
K/Na, approx. mole ratio	3.9	3.8

These compositions give good suds in washing dishes and in hand washing of fine fabrics.

In these compositions, methylethylcoconut amine oxide or diethylcoconutamine oxide can be substituted for dimethylcoconutamine oxide without substantially adversely affecting the physical characteristics or performance of the composition.

What is claimed is:

- An opaque viscous liquid detergent composition consisting essentially of:
  - from about 4% to about 10% of an alkali metal

- borate selected from the group consisting of sodium tetraborate decahydrate and potassium pentaborate;
 (b) from about 3% to about 10% of an aliphatic tertiary amine oxide having the general formula $R_1R_2R_3N\rightarrow O$ where R_1 is an alkyl radical containing from about 10 to about 16 carbon atoms and R_2 and R_3 are each selected from the group consisting of methyl and ethyl radicals, at least 50% of said amine oxide having an R_1 alkyl radical containing 12 carbon atoms;
 (c) from about 3% to about 15% of non-soap detergent selected from the water-soluble salts of the group of detergent anions consisting of RSO_4^- , $R(OC_2H_4)_xSO_4^-$ where x is an integer from 1 to 5,

- R being an alkyl radical containing about 9 to about 6 carbon atoms, and mixtures thereof;
 (d) from about 3% to about 10% of a salt of a hydrotrope anion of the group consisting of toluene sulfonate, benzene sulfonate, and xylene sulfonate;
 (e) from about 3.5% to about 6% silicate solids having an SiO_2/M_2O ratio of from about 16:1 to about 2.6:1 where M is selected from the group consisting of sodium and potassium;
 (f) from about 10% to about 30% of a salt of pyrophosphate anion; and the balance substantially (g) water;

the cations of the salts of the said detergent anions, of the salts of the said hydrotrope anions, and of the salts of the said pyrophosphate anion being selected from the group consisting of potassium, sodium, ethanolammonium, diethanolammonium, and triethanolammonium, the mole ratio of the total of potassium and alkanolammonium cations to sodium cations being greater than about 3:1.

2. An opaque viscous liquid detergent composition consisting essentially of:

- (a) from about 4% to about 10% of an alkali metal borate selected from the group consisting of sodium tetraborate decahydrate, and potassium pentaborate.
 (b) from about 3% to about 10% of an aliphatic tertiary amine oxide having the general formula $R_1R_2R_3N\rightarrow O$ where R_1 is an alkyl radical containing from about 10 to about 16 carbon atoms and R_2 and R_3 are each methyl radicals, at least about 50% of said amine oxide having an R_1 alkyl radical containing 12 carbon atoms;
 (c) from about 3% to about 15% of a sodium salt of a non-soap detergent anion selected from the group consisting of RSO_4^- , $R(OC_2H_4)_xSO_4^-$ where x is an integer from 1 to 5,

- R being an alkyl radical containing about 9 to about 16 carbon atoms, and mixtures thereof;
 (d) from about 3% to about 10% of potassium toluene sulfonate;
 (e) from about 10% to about 30% of potassium pyrophosphate; and the balance substantially (f) water.

3. An opaque viscous liquid detergent composition consisting essentially of:

- (a) from about 4% to about 10% of an alkali metal borate selected from the group consisting of sodium tetraborate decahydrate and potassium pentaborate.

- 5 (b) from about 3% to about 10% of an aliphatic tertiary amine oxide having the general formula $R_1R_2R_3N\rightarrow O$ where R_1 is an alkyl radical containing from about 10 to about 16 carbon atoms and R_2 and R_3 are each methyl radicals, at least about 50% of said amine oxide having an R_1 alkyl radical containing 12 carbon atoms;
 (c) from about 3% to about 15% of a sodium salt of a non-soap detergent anion selected from the group consisting of RSO_4^- , $R(OC_2H_4)_xSO_4^-$ where x is an integer from 1 to 5,

- R being an alkyl radical containing about 9 to about 16 carbon atoms, and mixtures thereof;
 (d) from about 3% to about 10% of potassium toluene sulfonate;
 (e) from about 3.5% to about 6% silicate solids of the composition $SiO_2:Na_2O$, their weight ratio being from about 1.6:1 to about 2.6:1;
 (f) from about 10% to about 30% of potassium pyrophosphate; and the balance substantially (g) water.

4. An opaque viscous liquid detergent composition consisting essentially of: (a) from about 4% to about 10% of sodium tetraborate decahydrate; (b) from about 3% to about 10% of coconut dimethyl amine oxide; (c) from about 3% to about 15% of a member selected from the group consisting of sodium dodecyl benzene sulfonate, sodium coconut sulfate and mixtures thereof; (d) from about 4% to about 6% of potassium toluene sulfonate; (e) from about 10% to about 30% of potassium pyrophosphate; and the balance substantially; (f) water.

- 35 5. An opaque viscous liquid detergent composition consisting essentially of:

- (a) 6.0% of dimethyldodecylamine oxide;
 (b) 6.0% of the triethanolamine salt of alkyl benzene sulfonate wherein the alkyl group is a mixture of tri-, tetra-, and pentapropylene and has an average carbon content of about 12;
 (c) 25.0% of potassium pyrophosphate;
 (d) 8.5% of potassium toluene sulfonate;
 (e) 5.0% of sodium tetraborate decahydrate;
 (f) 5.0% sodium silicate solids having an SiO_2/Na_2O ratio of 1.6; and
 (g) the balance water, the molar ratio of potassium and triethanolammonium to sodium being approximately 5.5.
